(57) CLAIM

The ornamental design for a jersey for a suitcase, as shown and described.

DESCRIPTION

FIG. 1 is a side view of a jersey for a suitcase shown in use; FIG. 2 is a perspective view of FIG. 1;

FIG. 3 is a top view of FIG. 1;

FIG. 4 is a bottom view of FIG. 1;

FIG. 5 is a perspective view of the jersey shown in FIG. 1;

FIG. 6 is a front view of the jersey shown in FIG. 1;

FIG. 7 is a rear view of the jersey shown in FIG. 1; and,

FIG. 8 is a right side view of the jersey shown in FIG. 1; the left side view being a mirror image thereof.

The broken line showing of the suitcase in FIGS. 1-4 is to show environment and forms no part of the claimed design.
